UNITED STATES PATENT OFFICE

WILLIAM M. RYAN AND CLYDE B. FAVERTY, OF CHICAGO, ILLINOIS, ASSIGNEES TO
RYAN CAR COMPANY, OF CHICAGO, ILLINOIS, A CORPORATION OF ILLINOIS

STEAM BOILER SYSTEM

Application filed March 2, 1931. Serial No. 519,491.

Our invention relates in general to steam boiler systems and more in particular to a circulating type of tube boiler of a character often referred to as a "semi-flash boiler". 5 In its most specific aspects the invention has to do with features which perform their major role during the cooling and firing up of the system.

There are fundamental shortcomings in 10 boiler systems of the character referred to, which manifest themselves principally during the firing up period. The deficiencies alluded to will be explained more fully in the body of the specification, but for the present it may be said that these deficiencies manifest themselves in too frequent burning of the tubes or circulating coils, and in requiring a somewhat greater length of time 15 to bring the system up to full capacity than should be required with the most satisfactory functioning of the system.

The principal object of the present invention is to improve steam boiler systems.

Another object is the provision of an improved starting method for steam boiler systems of the character referred to.

Another object is to increase the life of the circulating coils employed in such systems.

Another object is initially to promote circulation of fluid through the coils in the normal direction.

Another object is to present to the burner on initial firing a set of coils substantially filled with water, whereby the burning out 25 of tubes due to the overheating at the starting period is prevented.

Another object is to operate a boiler system so as to make the system immediately available for the building up of pressure therein 30 when the burner is ignited.

Other objects and features of the invention will be apparent from a consideration of the following detail description taken with the accompanying drawings, wherein,

45 Fig. 1 is a schematic lay-out of the system as applied to a particular type of installation, and

Fig. 2 shows the steam generating system somewhat more in detail.

50 In the system to which the present inven-

tion is applied, a steam generator is employed, including a burner about which are disposed a plurality of circulating coils comprising in general practice water pre-heating coils, evaporating coils and steam super-heating coils. Water is fed to the pre-heater coils by a force pump and this water is delivered from the pre-heater coils to the evaporator coils through an injector which draws additional water for the evaporating coils 60 from the bottom of a steam and water separating drum forming part of the system. The effluent from the evaporator coils is discharged tangentially at the top of the drum, unvaporized water particles falling to the 65 bottom of the drum and the steam remaining at the top of the drum, whence it is delivered by a pipe to the steam super-heating coils. From the steam super-heating coils the steam is delivered to the point of use, such as a 70 multi-cylinder steam engine for driving a rail car.

This type of steam generator is operated as a general rule on a closed system basis, exhaust steam being discharged into a condenser which delivers the condensate through 75 suitable means back into the system. A very important feature of a system of this character distinguishing it from the old type of steam locomotive is the fact that from a coal start, steam can be generated in a relatively 80 short length of time. When the system is used on a rail car, for example, such car is usually used on a portion of the transportation system where an ordinary locomotive is 85 unsatisfactory, due to long lay-overs or other conditions, which makes the new type rail car more desirable. It is found in actual practice that the system is allowed to cool 90 down, necessitating frequent starting from a cold system, as a rule much oftener than is the case with a steam locomotive.

When the system cools, a vacuum is created in the steam containing portions, and this has the effect of drawing the water out of the tubes, which normally hold the water, and into portions of the system which normally carry steam. The relatively larger body of steam in the top of the drum, for example, causes much of the water to be drawn up into 100

the drum. On starting, the coils will then contain less than the normal and required amount of water for proper operation and due to the shortage of water over-heating 6 may result with an injury to the coils. The evaporating and steam super-heating coils are closest to the burner and will receive the heat of the burner more quickly and more intensely than the pre-heater coils. The residual 10 moisture in these coils is quickly driven off, thereby making the coils substantially bone-dry and permitting them to become intensely hot, due to their close exposure to the burner. Such circulation as is initially set up in the first stages of starting will rather 15 tend to cause reversed circulation of the water in the boilers than normal circulation and so will delay the normal movement of the water from the pre-heating coils into the evaporating coils. This is shown by the fact 20 that often the injector will not begin to function until the steam pressure has reached as high as 400 lbs. When the circulation is finally set up so that water is supplied to the 25 overheated tubes, these tubes operate almost as a full flash boiler. Since this is not the intended manner of operation of these tubes or coils, the system will not function with satisfaction until the overheated coils have 30 been brought substantially back to a normal temperature and operative circulation established. In the starting of the present type of steam system without the improvements of 35 our invention, we find that the steam pressure increases in steps, a relatively rapid rise in pressure being followed by a lag period in which the pressure will remain substantially uniform or even may be lowered slightly.

According to the general method practiced by us, we overcome these difficulties by 40 breaking the vacuum in the system during the cooling period so that the coils on initial starting will be substantially filled with water, with the exception of course of the 45 steam super-heating coils, which in the design of the system are not to contain water. Near the discharge point of the superheating coils we provide bleeder means for venting the high pressure steam line, this venting 50 means being operative until the system attains a pre-determined pressure, at which time normal operating conditions have been brought about and the system is substantially ready to supply steam at the normal operating pressure.

Referring now to Fig. 1 of the drawings, we show a steam generator 10, (shown more in detail in Fig. 2), a steam engine 11, a condenser 12, receiving discharge steam from 60 the engine, a water supply tank 13, and a pump 14 for drawing water from the supply tank and delivering it under pressure to the steam generator, the pump being operated by suitable means, for example, an electric motor 16.

Referring now to Fig. 2, the steam generating system includes a main burner 17 adapted to be supplied with fuel vaporized and forced under pressure to the burner with air from a blower 18. The fuel delivered into the passageway 19 in an atomized condition is vaporized by contact with a hot plate 21, which is maintained at an elevated temperature by a pilot burner 22 of suitable type. In the form shown a suitable temperature is initially imparted to the pilot burner by electrical heating coils 23. A burner of this character is operated under conditions and in a manner not of prime importance in connection with the present invention. It is sufficient to state that the burner operates at a very elevated temperature, producing a clear blue non-radiant type of flame, which is visible under normal operating conditions not more than an inch away from the burner. It will be understood that the character and intensity of this flame is important in connection with the operation of the burner, as it will quickly cause an overheating of the tubes, if they are not supplied with sufficient water to keep the temperature thereof below any possible danger point.

Around the burner and within the casing 24 are grouped the coils, including evaporating coils 26, steam super-heating coils 27 and water pre-heating coils 28. Water is delivered to the coils 28 through a pipe 29 and the pre-heater coils deliver water to a pipe 31 communicating with an injector 32, which through a pipe 33 draws additional water from the bottom of a drum 34. From the injector water is delivered through a pipe 36 to the evaporator coils 26 and the steam mixed with water particles with some water is discharged from the evaporating coils through a pipe 37 into the top of the drum 34. The pipe 37 preferably has an outlet part within the drum disposed tangentially thereof to facilitate separation of water and steam, the water falling to the bottom of the drum and the steam remaining in the top portion thereof. A pipe 38 communicating with the top of the drum withdraws steam therefrom for delivery to the super-heating coils 27 and the super-heated steam is delivered from the super-heating coils through a pipe 39, which, through suitable control means, is adapted to be delivered to the place or places needed.

In order to prevent the development of a vacuum in the system when it is cooled down, with the undesirable results explained, we provide a vacuum breaker 41 in the upper part of the drum, although it will be obvious that this vacuum breaker might be placed in substantially any portion of the system, which normally holds steam during operation. This vacuum breaker may be of the types well known in the industries. In

the present form we show a body portion with a valve seat 42 with which a valve 43 is adapted to cooperate to close the valve. This valve is carried on a stem 43 extending 5 through the valve casing with suitable packing (not shown). A spring 46 determines the relative pressures at which the valve operates. Normally, the valve would operate full automatically, but the projecting portion 10 of the valve stem affords a means for manually operating the valve should occasion require.

Connected into the pipe 39, we show a somewhat schematic valve means for venting the high pressure line until a pre-determined pressure is developed therein. This 15 includes a pipe 47 connected into the pipe 39, which communicates with a valve casing 47. This valve casing contains a valve, including 20 a seat 48 and a valve body 49, through the operation of which flow of steam through the pipe 47 is controlled. For the operation of the valve 47 a diaphragm type of valve 51 is provided having a diaphragm 52, one side 25 of which is under the same pressure as the pipe 47 through a small pipe 53 communicating with the pipe 47 and one side of the diaphragm. A spring 54 at the opposite side of the diaphragm opposes a pre-determined 30 pressure against the steam pressure. The diaphragm has connected thereto a valve stem 56, which extends through the two valve casings and carries the valve 49, which thereby is caused to open or close by the movement of the diaphragm 52. The spring 54 is set to exert any pre-determined pressure 35 and will, therefore, hold the valve in an open position until a sufficient steam pressure is developed at the opposite side of the dia- 40 phragm to overcome the force of the spring and close the valve.

The steam discharged through the valve casing 47 is delivered to a pipe 57, which pipe 57 may communicate with any portion of the 45 system. One very satisfactory arrangement is shown in Fig. 1, in which the steam from the pipe 57 is discharged onto the engine 11, thereby warming this engine up during the starting period of the steam generating system 50 so that when the steam has reached the required pressure, the system as a whole is in the most efficient condition for operation. This provision is found to be very desirable during the cold weather when the engines 55 which are usually placed under the car are exposed to the outside temperature and may be quite cold.

Since considerable electrical current is employed for the operation of various controls 60 and the like, (not shown) an auxiliary steam engine 58 is usually provided for driving a generator 59, which supplies power to the electrical portions of the system. This auxiliary engine may also be fed with steam bled 65 from the pipe 39 during the starting up

period, a pipe 61 being shown communicating with the pipe 57 for the purpose. Suitable valve mechanism is provided for directing the steam from the pipe 57 to the point where it is to be used. It will be understood 70 that this steam may be discharged into any part of the system or for that matter into the atmosphere. A pipe 62 is indicated in Fig. 1 for this purpose.

From the foregoing description it is believed that the main operating features of the system will be understood. Taking a hot system with full steam pressure and allowing it to cool, the vacuum breaker allows air from the outside to enter the system to take 80 the place of the steam normally present in parts thereof. When the system is standing cold relatively large amounts of air at close to atmospheric pressure are present. During the firing period some of this air undoubtedly is driven by expansion directly out through the bleeder opening, but parts of this air will be mixed with the steam as it is generated and eventually will find its way up to the condenser either through the 85 exhaust pipe 63 from the auxiliary engine or through the exhaust pipe 64 from the main engine. We provide means effective to exhaust this air so that the system when brought completely up to operating pressure 90 95 will consist substantially entirely of water and steam.

The condenser discharges its condensate through a pipe 66 into a water supply tank 13, this pipe 66 discharging below the surface of the water for several reasons readily understood, among the most important being to build up just sufficient back pressure in the condenser to cause the proper distribution of exhaust steam therein. If uncondensed 100 steam, which may be present, as well as air which was sucked into the system on cooling, is delivered under water to the tank 13 it readily escapes out through a vent opening 105 110 115 120 125 130 67 provided in the tank. It is readily seen that a very short time after the system starts to operate, even though the steam pressure is still low, substantially all of the air will have been driven off.

In connection with the relieving of a vacuum in the system to prevent displacement of water, substantially the same result can take place between the condenser and water supply tank when the condenser cools below the normal operating temperature thereof. For this reason we also provide a vacuum breaking valve 67 at a suitable place in the condenser. Air admitted to the condenser through this valve is quickly exhausted through the opening 67 when the condenser again starts functioning. Although as a general rule the condenser will be maintained at a sufficiently high temperature during operating to prevent the creation of an undesirable vacuum therein, in very cold weather if

the car stands for some time, for example in a station for discharging and taking on passengers and baggage, the condenser may be cooled to such an extent as to create a partial vacuum. The valve 68 is designed to relieve this vacuum before it is sufficiently low to allow air above the water in the tank 13 to force the water back into the condenser. In extremely cold weather any large amount of water driven up into the condenser from the tank 13 might freeze in such a way as to cause a temporary stoppage of the system. The relief valve 68 functions also to relieve the vacuum in the condenser when the system is shut down, occasioned by extinguishing the main burner.

In Fig. 1 the ordinary steam line 39 communicating with the engine will not pass steam to the engine during the firing period for several obvious reasons. In the first place this steam line is controlled by valves including throttle valves, which normally are closed and so cut off the flow of steam to the engine. It will be understood that the showing of Fig. 1 is to a large extent schematic and no throttle valve is shown. In addition, the steam admitted to the engine from the throttle valve delivers steam through the valve system to the tops of the cylinder heads for driving the engine. It will readily be understood that although some heating effect would be obtained in this way, there is nothing approaching the results obtained when the steam is passed through the sump of the engine, as the drawings illustrate.

From the description of the system, it is clear that we employ a new starting method, practiced, it is true, preferably by a system of the character shown, but adapted to be practiced in other ways. Since the steps of the method are clearly understandable by a description of the apparatus, no detailed explanation of the method will be made.

That beneficial results are obtained by means of our system and the practice of our method appears clear when the operation of the injector on starting is considered. In the old system without the vacuum relief means and bleeder means of our invention, the injector usually failed to operate until approximately 400 lbs. of pressure had been developed in the system, the system being designed to operate at about 650 lbs. pressure. It is clear that during this time such movement of fluid as might have taken place within the coils was not of a character either to protect the tubes or to obtain the best and quickest starting results,—in other words, normal circulation had not been established.

We have found that with the method of our invention as practised with the apparatus shown, the injector starts operating when not more than 50 lbs. of pressure has been developed in the system. This means that when the temperature of the coils is still

relatively low normal circulation has already been established. We further attain the objects of the invention by the selection of certain specific types of materials from which to construct the coils. The coils immediately adjacent to the burner are formed of material having relatively low thermal conductivity, while those farther away from the burner have relatively high thermal conductivity. In actual practice the material used in the evaporating and super-heating coils is a high grade alloy steel having relatively high heat resistance, while the pre-heater coils are constructed of an ordinary good grade of steel tubing, having substantially the same heat conductivity in actual practice as ordinary pure iron.

The operation and function of the steel tubing of our selection as is follows. When the burner is first fired with the coils cold, ordinary steel tubing would absorb a very large proportion of the heat, leaving only a relatively small residual amount of heat for the pre-heater coils. This would be true, particularly when the system was very cold, on account of the relatively great temperature drop between the burner and tubes. When a metal with relatively more heat resistance is used adjacent the burner, less heat is absorbed, and more heat reaches the farther removed pre-heater coils. Since the circulatory movement is from the coils farthest away from the burner, toward those closest to the burner, the effect on the circulation of different types of metals, at least in the early stages, is manifest. Relatively low heat conductivity in the coils adjacent the burner tends to aid in establishing normal circulation in the early stages from a fully cold start; while evaporating coils of high thermal conductivity tend to cause reverse circulation, or arrested circulation at this time.

Not only does this selection of materials aid in the establishment of normal operation early during the firing period, but the tubes in the immediate fire zone are further protected by the high quality and greater strength of the alloy steel. In case the tubes are overheated, due to shortage of water in the tubes, possibility of damage is lessened.

We wish to call attention to the position of the drum 34, the bottom of the drum being substantially even with the top of the coils. This permits the flow of water by gravity to the coils when the system is cooled, thereby insuring that the tubes will be entirely filled with water when the system is started. It will be understood that substantially the same result can be obtained if the drum is approximately even with the tubes, but this would be only if more than a usually large supply of water were available in the tube and drum portion of the system. For ordi-

nary operation the elevated position of the drum is to be preferred.

What I claim as new and desire to protect by Letters Patent of the United States is:—

- 1. In a steam boiler system, a burner, a plurality of circulating coils disposed about the burner, a steam and water separating drum, connections between the coils and said drum, and vacuum breaking means at the 10 top of the drum to prevent water from being sucked out of the coils and into the drum when the system is cooled.
- 2. In a steam boiler system, a burner, a plurality of circulating tubes disposed about 15 the burner, a steam and water separating drum, connections between the tubes and drum, a steam line extending from the top of the drum for delivering steam to a source of power, and means for venting said steam 20 line during the firing up period of the boiler, said venting means including a pressure responsive valve adapted to close in response to increased pressure on the inlet side thereof.
- 3. In a steam boiler system, a burner, a plurality of circulating tubes disposed about the burner, a steam and water separating drum, connections between the tubes and drum, a steam line extending from the top 25 of the drum for delivering steam to a source of power, means for venting said steam line during the firing up period of the boiler, and vacuum breaking means at the drum to prevent water from being sucked out of the 30 tubes and into the drum when the system is cooled.
- 4. In a steam boiler system, a burner, circulating evaporating coils and water pre-heating coils disposed about the burner, a 35 steam and water separating drum adapted to contain a body of water and a body of superimposed steam while the system is operating, connections between said coils and the water containing portion of the drum, and vacuum 40 breaking means in the steam portion of the drum to prevent drawing water from the coils into the drum.
- 5. In a steam boiler system, a burner, water pre-heating, evaporating and steam super-heating coils disposed about the burner, a 45 steam and water separating drum having water and steam connections to said coils, and means for venting the superheater coils during the firing period of the boiler, whereby 50 normal water and steam circulation is promoted, said venting means including a pressure responsive valve adapted to close in response to increased pressure on the inlet side thereof.
- 6. In a steam boiler system, a burner, water pre-heating, evaporating and steam super-heating coils disposed about the burner, a 55 steam and water separating drum having water and steam connections to said coils, means 60 for venting the super-heater coils during the

firing period of the boiler whereby normal water and steam circulation is promoted, and vacuum breaking means in the drum to prevent drawing water from the coils into the drum when the system is cooled, whereby water is available in the coils at all times during the firing period. 70

7. In a steam boiler system, a burner, water pre-heating, evaporating, and steam super-heating coils disposed about the burner, 75 a steam and water separating drum having water and steam connections, said steam super-heating coils extending from the top of the drum and adapted to deliver steam to a source of power, means for initially bleeding the super-heating coils when the burner is first ignited, and means for rendering the bleeder means inoperative when a predetermined steam pressure is attained in the super-heating coils. 80

8. In a steam boiler system, a burner, water pre-heating, evaporating, and steam super-heating coils disposed about the burner, a steam and water separating drum having water and steam connections, said steam super-heating coils extending from the top 90 of the drum and adapted to deliver steam to a source of power, means for initially bleeding the super-heating coils when the burner is first ignited, means for rendering the bleeder means inoperative when a predetermined steam pressure is attained in the system, and means for relieving the vacuum in the system when the burner is extinguished and the system allowed to cool. 95

9. In a steam boiler system, a burner, water pre-heating, evaporating and steam super-heating coils, a steam and water separating drum having connections to said coils, means for admitting air to the drum and coils to relieve vacuum created by condensation of steam when the system is cooled, and means for removing said air from the system when such system is again operated to produce steam. 100

10. The method of starting a steam system of the type comprising a burner, circulating coils including steam super-heating coils, and a steam and water separating drum for delivering saturated steam to said super-heating coils, which comprises firing the burner, and bleeding the super-heating coils to initiate substantially immediate normal circulation, and closing said bleeding means when a pre-determined steam pressure is attained 115 in the super-heating coils. 120

11. In a steam boiler system, a burner, a plurality of circulating coils disposed about the burner, a steam and water separating drum positioned above the coils, connections 125 between the coils and drum and vacuum breaking means to prevent the water from being sucked up into the drum and out of the coils when the system is cooled, the position of the drum above the coils permitting 130

the water to flow by gravity from the drum into the coils when the vacuum in the system is relieved.

5 In witness whereof, we hereunto subscribe our names this 26th day of January, 1931.

WILLIAM M. RYAN.
